UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

KEY-CHANGING LOCK.

Application filed August 7, 1924. Serial No. 730,655.

This invention relates to improvements in changeable combination key locks and particularly to such as are adaptable for use with safe deposit boxes, one object of the 5 invention being to facilitate the operation of changing the setting of the mechanism for operation with the use of a different key than the one for which the mechanism may have been originally set. 10 A further object is to provide in a lock of the type specified, simple and improved means whereby a key may be released from the lock while the bolt is in retracted position, to permit the insertion of a new change 15 key, and to so construct and arrange such means that the key by which its operation is controlled may be inserted through the exposed face of the lock casing. 20 With these and other objects in view, the invention consists in certain novel features of construction and combinations of parts as hereinafter set forth and pointed out in the claims.

In the accompanying drawings; 25 Figure 1 is a view in elevation of the lock with the cover plate and the change key tumblers and fences and the guard key tumblers removed, and showing positions of the parts when the bolt is projected;

30 Figure 2 is a similar view but showing the tumbler and fence assembled;

Figure 3 is an elevation showing the bolt in retracted position, and the tumbler mechanism for the change and guard keys removed;

35 Figure 4 is a view similar to Figure 3 with the tumbler and guard mechanisms removed;

Figures 5, 6, 7 and 8 are detail views;

40 Figure 9 is a front view showing the lock casing;

Figure 10 is a side view with the casing partly broken away to expose parts of the mechanism, and

Figure 11 is a view of the releasing key.

45 The lock casing is represented at 1 and the cover plate thereof at 2. A sliding bolt 3 is mounted within the casing 1 and is formed with a recess 4, with shoulders in which, the cam 5 on a key hub or plug 6 is 50 cooperable to withdraw or project the bolt, and in order to limit the return or counter-clockwise movement of said plug and insure the proper normal position of the same, a fixed stop 7 is provided to be engaged by the cam 5. The tail portion of the

bolt is provided with an elongated slot 8 through which a post 9 (rigid with the casing) passes, and thus the bolt is guided in its reciprocating movements. The tail portion of the bolt is also made with a beveled 60 or inclined edge 10 and with a hole 11 for purposes hereinafter explained. Spring-pressed change-key tumblers 12 are pivotally mounted on the post 9 and in the gatings of these tumblers, fingers 13 on slideable fences 14 are adapted to enter when the tumblers shall have been moved by a key to bring said gatings into alignment. The fences are mounted upon the bolt in rear of the head thereof and are provided with 70 elongated slots 15 for the passage of posts or studs 16 on said bolt, whereby the fences are guided in their movements. The fences are provided each with a plurality of notches 16^a to receive a finger 17 on a stationary 75 spline 18, all as fully shown and described in patent to W. H. Taylor, March 6th, 1906 and designated by No. 814,335.

The lock is equipped with guard key mechanism and the specific mechanism 80 which may be employed will now be described:

A plurality of spring-pressed guard key tumblers 19 are pivotally mounted on a fixed post or stud 20 and the gatings of these tumblers (when brought into alignment with the use of a proper guard key) are adapted to receive a fence 21 projecting from a guard releasing tumbler 22,—the latter having an open slot 23 at one end to receive the post 85 or stud 20 and a closed slot 24 near its other end, through which latter slot, a fixed post 25 passes. A spring-pressed guard latch 26 lies parallel with the releasing tumbler 22 and is mounted to turn on the post or stud 90

25. At its free end, the guard latch 26 is provided with a guard stop 27 which normally is in the path of a stop shoulder 28 on the key plug and prevents such extent of turning of the latter as would effect retraction of the bolt. The guard latch 26 is provided between its ends with a cam slot 29 into which a pin 30 projecting from the guard releasing tumbler 22 projects, so that when said tumbler 22 is moved longitudinally in one direction, the latch 26 will be so moved on its pivotal mounting as to withdraw the hook or stop 27 out of the path of the stop shoulder 28 on the key hub 6, and so that when said tumbler 22 is moved in 100 105 110 115

the other direction, the hook or stop 27 of the latch 26 may be moved by its spring into the path of said stop shoulder 28.

A spring pressed lever 31 is pivotally mounted on the post or stud 20 and extends rearwardly therefrom, said lever being provided at its free rear end with a lateral beveled lug or projection 32 which is normally disposed behind the beveled rear edge 10 of the tail of the bolt 3, and between the lug or projection 32 and a lug or tooth 33 on the guard releasing tumbler 22, a short arm or lever 34 is disposed and pivotally mounted on the post 25. In order that the 15 arm or lever 34 shall be held frictionally in the position to which it may be moved, a coiled spring 34^a is located on the post 25 and bears against the hub of said arm or lever and against the cover plate of the 20 casing.

An approximately U-shaped lever 35 (or a plurality of such levers) is pivotally mounted on the post 25 and is formed with two arms 36 and 37 separated by a space 38, and 25 said lever (or levers) will be normally so disposed by the action of spring means 39, that the arm 36 will be located in the path of the cam 5 on the key hub and prevent said hub and cam from being turned far enough 30 to permit withdrawal of the change key when the bolt is in retracted position. The exposed face of the casing is provided with a key-hole 40 so located that the head of a key 43 inserted through said key-hole will 35 become disposed in the space 38 which separates the arms 36-37 of lever 35. When such key, thus inserted, is turned clockwise, its head will engage the arm 37 of lever 35 and so operate said lever as to move the arm 40 thereof, out of the path of the key-hub cam 5, and thus permit the key hub to be turned sufficiently far to permit withdrawal of the change key.

In the operation of unlocking, a guard key 41 is inserted into the hub or plug 6 and turned in clockwise direction. The key, after setting the guard tumblers to align their gatings with the fence 21 will contact at 42 on the guard releasing tumbler 22, and cause 45 the latter to move to the left, and at the same time, cooperation of the pin 30 on said tumbler with the cam slot 29 in the guard latch 26, will cause the latter to swing on its pivotal mounting so that the hook or guard stop 27 will be carried out of the path of the 50 stop shoulder 28 on the key-hub or plug 6, thus permitting the free turning of the latter and the change key subsequently inserted. The guard key is then turned back 55 and removed. A change key 42 will now be inserted into the key hub or plug 6 and turned to retract the bolt, as will be readily understood. As the bolt moves inwardly, its beveled rear end 10 will contact with the 60 beveled end lug 32 of the lever 31, which in

turn will swing the small lever 34 to the right, carrying with it the guard releasing tumbler 22, thus moving the pin 30 in the cam slot 29 of the lever 26 and allowing the latter to spring into position with its guard 70 stop 27 in normal locking position ready to again lock the key plug after it shall have been turned to project the bolt and thus prevent said plug from being turned a second time sufficiently to retract the bolt. 75

To change the key setting, the bolt will first be fully retracted and while in this position, releasing key 43 (Fig. 11) will be inserted through the key hole 40 (the end of the key entering the hole 11 in the tail portion of the bolt 3) and turned clockwise. As the hole 11 forms the inner bearing for the key 43, it is evident that the lever 35 cannot be operated except when the bolt is in its fully retracted position. The bit of the key 80 will contact with the arm 37 of lever 35, causing the latter to so turn on its pivot mounting as to withdraw the arm 36 of said lever from the path of the key plug cam 5, thereby enabling the plug to be turned far 85 enough for the change key to be withdrawn from the plug. A new change key of the desired combination may then be inserted and the bolt projected and the lock will then be set to the new key. 90

Having fully described my invention what I claim as new and desire to secure by Letters-Patent, is:—

1. In a changeable combination key lock, the combination with a case, a bolt, and key 100 operated means including a key plug and cam, of a lever pivoted at one end and having two arms forming a space between them, spring means holding said lever in normal position with one of its arms in the path of the cam on the key plug, the other arm of said lever constituting a key engaging arm, the case having a key hole positioned to permit the insertion of a key between the arms of said lever, whereby when said key is 110 turned it will engage the key engaging arm of said lever and swing said lever in a manner to move its other arm out of the path of the key plug cam. 105

2. In a changeable combination key lock, 115 the combination with a bolt and key operated means for actuating the same, of a key actuated spring pressed lever operable to normally limit a member of the key operated means, said lever being approximately 120 U-shaped, means normally holding said lever in limiting position, and a key insertable between the arms of said lever and cooperable with one of them to move said lever to releasing position. 125

3. In a lock of the character described, the combination of a case, a bolt having a beveled rear end portion, a key plug having a stop shoulder, a bolt operating cam associated with said plug, change key tumbler 130

mechanism, guard key mechanism including a spring-pressed pivoted guard latch having a stop cooperable with the shoulder on the key plug, a sliding guard releasing tumbler 5 having cam connection with said pivoted guard latch and movable in one direction by a guard key to effect withdrawal of the guard latch stop from the path of the shoulder on the key, a lug on said tumbler, a pivoted lever having a beveled free end portion 10 to be engaged by the beveled rear end portion of the bolt, a pivoted member between the beveled portion of said lever and the lug on said guard releasing tumbler, guard key 15 tumbler mechanism, and a fence for said guard key tumbler mechanism, carried by said guard releasing tumbler, and a key re-

leased lever normally limiting the turning of the key plug by means of a change key.

4. In a changeable combination key lock, 20 the combination with a casing having a key hole in its front face, of a bolt, and key releasing means, said bolt having a bearing for a releasing key inserted through the key hole in the front face of the casing, the bearing for the key being so located that it will be positioned to receive the key only when the bolt is in retracted position, whereby the releasing means cannot be operated except 25 when the bolt is in its retracted position. 30

In testimony whereof, I have signed this specification.

ROLLIN C. LEWIS.
